TOOL MOUNTING

Filed Aug. 16, 1928

Inventor:
Elmer G. Gartin
by Louis A. Maxam.

Atty.

UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

TOOL MOUNTING

Application filed August 16, 1928. Serial No. 299,915.

My invention relates to tool mountings and more particularly to adjustable mountings for pneumatic tools adapted for rock drilling.

5 An object of my invention is to provide an improved tool mounting. Another object of my invention is to provide an improved mounting for a tool of the rock drill type. A further object of my invention is to provide 10 an improved mounting for a rock drill which may be readily adjusted to accommodate drills of different size. A still further object of the invention is the provision of improved 15 mounting for rock drilling devices adapted to accommodate such devices of different sizes and to feed them toward and from the work. Yet another object of the invention is to provide 20 an improved mounting in which parts extending above the top of the tool when the same is clamped in position may be avoided. A still further object is the provision of a 25 tool mounting permitting the bringing of the tool axis into proper parallelism with the feeding mechanism. Other objects and advantages of the invention will hereinafter more fully appear.

In the accompanying drawing I have shown for purposes of illustration one embodiment which my invention may assume in 30 practice.

In this drawing,—

Fig. 1 is a view partially in side elevation and partially in longitudinal vertical section through the illustrative embodiment of my 35 improved tool mounting, the view showing a tool mounted in position.

Fig. 2 is a transverse section on the line 2—2 of Fig. 1.

Fig. 3 is a plan view of the improved 40 mounting without a tool mounted thereon.

To demonstrate its mode of use, I have shown the illustrative embodiment of my improved tool mounting, in Fig. 1, employed in the support of a percussive motor 1. The motor 1 has a handle 2, a cylinder 3, and a chuck housing 4.

A trunnion 5 supports a shell 6 which is provided with the usual guides 7 in which gibs 8 upon a cradle element 9 are slidably supported. The cradle 9 carries a feed nut

10 with which a feed screw 11, rotated by a feed handle 12, cooperates to move the cradle toward and from the work.

The cradle 9 carries at its rear end a clamping mechanism for holding the handle of the 55 drill 1. This clamping mechanism, generally designated 14, comprises a seat member 15 having a recess 16 to receive and support the handle and a clamp element 17 overlies the handle and is held in place by a nut 18 and stud 19. Forwardly of the clamp 14 the cradle 9 is provided with guide gibs 21 arranged parallel to the gibs 8 but extending toward 60 each other. Upon these gibs is mounted a sliding carriage 22 having grooves 23 by 65 means of which the carriage is positioned for sliding movement along the gibs 21. Suitable means is provided for effecting an interlocking connection between the carriage 22 and the drill 1. Herein, upstanding arms 24 70 upon the carriage carry screws 25 which are adapted to engage threaded openings in the chuck housing 4 of the drilling tool 1.

When the handle 2 of the tool 1 is clamped in the clamping device 14 and the screws 25 75 are threadedly engaged in holes in the chuck housing 4, the tool 1 is securely mounted in the cradle. It is obvious that tools of different sizes may be employed with the same cradle since the slidable mounting of the carriage 22 permits different lengths of tools to be received.

From the foregoing description it will be evident that I have provided a simple, readily adjustable, universal tool mounting for use 85 in connection with ordinary pneumatic tools of the hand type, a mounting in which different sizes of tools may be supported and in each case rigidly held in position. It will further be noted that the clamping device is 90 of such a character that no part thereof extends above the top of the tool which it supports and that thereby a very compact arrangement is provided. It will likewise be observed that the screws 25 permit lateral 95 adjustment of the tool supported between them so that the axis of the chuck may be brought into the same plane with the axis of the feed screw.

While I have in this application specifical- 100

ly described one form which my invention may assume in practice, it will be understood that this form of the same is shown for purposes of illustration and that the invention 5 may be modified and embodied in various other forms without departing from its spirit or the scope of the appended claims.

What I claim as new and desire to secure by Letters Patent is:

10 1. A tool mounting comprising a cradle, a clamping device for clamping a tool rigidly to said cradle at one end, a second tool holding means adjustably mounted on said cradle, and means for securing the tool rigidly to 15 said second tool holding means and including a pair of set screws engaging the opposite sides of the tool.

2. A mounting for rock drills comprising a cradle, a clamping device on the cradle 20 adapted to cooperate with a part of a rock drill to clamp the same to said cradle adjacent one end, a second tool holding means carried by the cradle presenting a pair of projecting portions adapted to receive an 25 other part of the rock drill between them, and means carried by said projecting portions and including independently adjustable holding elements each interengaging with 30 said second part of the rock drill for holding the same.

3. A mounting for rock drills comprising a cradle, a clamping device on the cradle adapted to cooperate with a part of a rock 35 drill to clamp the same to said cradle adjacent one end, a member carried by the cradle presenting a pair of upstanding portions having free open ends and adapted to receive a second part of the rock drill between them, and means carried by said member and including independently adjustable holding 40 elements each interengaging with said second part of the rock drill below said free ends to hold the drill.

4. A mounting for rock drills comprising 45 a cradle, a clamping device on the cradle adapted to cooperate with a part of a rock drill to clamp the same to said cradle adjacent one end, a member carried by the cradle presenting a pair of upstanding portions 50 having free open ends and adapted to receive a second part of the rock drill between them, and means carried by said member and including independently adjustable holding elements each interengaging with said second 55 part of the rock drill below said free ends to hold the drill in position, said member being movable longitudinally relative to said cradle.

5. A mounting for rock drills comprising 60 a cradle, a clamping device on the cradle adapted to cooperate with a part of a rock drill to clamp the same adjacent one end, a member carried by the cradle adjacent the other end, said member presenting a pair of 65 parallel upstanding portions adapted to re-

ceive another part of the rock drill between them, and a pair of screws carried by said upstanding portions and extending inwardly to interengage with said second part of the rock drill.

6. In a rock drilling mechanism, a guide shell, a cradle slidably guided on said shell, a rock drill, and means for positioning and holding the rock drill on said cradle including an adjustable device engaging a rear portion of the drill for rigidly securing the rear end of the drill in position on said cradle, and an adjustable device engaging a forward portion of the drill for rigidly securing the forward end of the drill against vertical displacement on the cradle and including a pair of set screws engaging the opposite sides of the drill.

7. In a rock drilling mechanism, a guide shell, a cradle slidably guided on said shell, a rock drill, and means for positioning and holding the rock drill on said cradle including an adjustable device engaging a rear portion of the drill for rigidly securing the rear end of the drill in position on said cradle, and an adjustable device engaging a forward portion of the drill for rigidly securing the forward end of the drill against vertical displacement on the cradle and including a pair of set screws engaging the opposite sides of the drill, said latter device being adjustable in a longitudinal direction relative to the cradle to vary the distance between said devices to enable drills of different lengths to be secured in position on said cradle.

8. In a rock drilling mechanism, a guide shell, a cradle slidably guided on said shell, a rock drill, and means for positioning and holding the rock drill on said cradle including an adjustable device engaging a rear portion of the drill for rigidly securing the rear end of the drill in position on said cradle, and an adjustable device engaging a forward portion of the drill for rigidly securing the forward end of the drill against vertical displacement on the cradle, and including elements adjustable in a direction transversely of the cradle and engaging the sides of a forward portion of the drill for laterally positioning the drill on said cradle and for rigidly holding the drill in such position.

9. In a rock drilling mechanism, a guide shell, a cradle slidably guided on said shell, a rock drill, and means for positioning and holding the rock drill on said cradle including an adjustable device engaging a rear portion of the drill for rigidly securing the rear end of the drill in position on said cradle, and an adjustable device engaging a forward portion of the drill for rigidly securing the forward end of the drill against vertical displacement on the cradle including a member slidably guided on said cradle at the forward end thereof and forming a support for the front end of the drill, and devices carried by said

slidable member adjustable in a direction transversely of the cradle and interengaging the sides of a bottom portion of the drill for rigidly securing said drill to said slidable member.

- 5 10. In a rock drilling mechanism, a guide shell, a cradle slidably guided on said shell, a rock drill, and means for positioning and holding the rock drill on said cradle including
10 an adjustable device engaging a rear portion of the drill for rigidly securing the rear end of the drill in position on said cradle, and an adjustable device engaging a forward portion of the drill for rigidly securing the forward
15 15 end of the drill against vertical displacement on the cradle including a member slidably guided on said cradle and forming a support for the front end of the drill, said member having upstanding side portions projecting along the sides of the bottom portion of the drill and set screws carried by said side portions and adjustable in a direction transversely of the cradle for interengaging a part of the drill to rigidly secure the drill
20 25 to said slidable member.

In testimony whereof I affix my signature.
ELMER G. GARTIN.
